UNITED STATES PATENT OFFICE.

WILLIE OWEN THOMAS, OF JANEVILLE, WISCONSIN, ASSIGNEE TO GWEN THOMAS
MOTOR CAR COMPANY, OF JANEVILLE, WISCONSIN, A CORPORATION OF WIS-
CONSIN.

MUFFLER.

956,785.

Specification of Letters Patent.

Patented May 3, 1910.

Application filed June 16, 1909. Serial No. 502,409.

To all whom it may concern:

Be it known that I, WILLIE OWEN THOMAS, a subject of the King of Great Britain, and residing at the city of Janesville, county of Rock, and State of Wisconsin, have invented certain new and useful Improvements in Mufflers, of which the following is a specification.

This invention relates to improvements in 10 mufflers and refers more particularly to a construction adapted for use with automobiles and the like to muffle the explosive noise from the exhaust side of the engine.

Among the salient objects of the invention are to provide a construction in which the explosive noise from the exhaust side of the engine is obviated and the gas discharged in a steady stream by passing the latter through a series of substantially closed elongated chambers serially connected together by constricted passages; to provide a construction in which the muffler may consist of a single pipe or conduit provided with said chambers and constricted passages and 25 which dispenses with the usual large and more or less clumsy muffler chamber; to provide a construction which is of relatively light weight, simple and economical in manufacture and at the same time performs its 30 function in a reliable and efficient manner; and in general to provide improved constructions of the character referred to.

The invention consists in the matters hereinafter described and more particularly 35 pointed out in the appended claims.

In the drawings Figure 1 is a fragmentary longitudinal sectional view of a preferred embodiment of my invention. Fig. 2 is a transverse sectional view taken on line 2, 2 40 of Fig. 1 and looking in the direction of the arrows. Fig. 3 is a view similar to Fig. 1 but showing a somewhat modified construction. Fig. 4 is a transverse sectional view taken on lines 4, 4 of Fig. 3 and looking in 45 the direction of the arrows.

In automobiles and similar vehicles the explosive noise of the gas from the exhaust side of the engine is such as to necessitate the use of mufflers. In the constructions now in 50 use the exhaust is discharged into a relatively large separate muffler chamber before it passes into the atmosphere. This muffler chamber which is secured to the chassis of the vehicle is more or less clumsy and takes 55 up considerable amount of space. Moreover

it has been found that in order to render it at all times efficient it has been necessary to provide it with lining and valve mechanisms. In the present invention the usual muffler chamber is dispensed with and the 60 exhaust gas discharged through a single pipe connected to the exhaust.

Referring to the drawings 1 designates as a whole a muffler pipe comprising a series of relatively narrow elongated chambers 2 65 communicating with each other through constricted passages 3. These passages are formed by merely flattening the sides of the pipe together in the manner shown more clearly in Fig. 2. The act of forming these 70 passages, of course, divides the pipe into a plurality of chambers 2 in an obvious manner. The exhaust gas after it passes through the pipe is preferably discharged through a relatively narrow opening 4 formed by flattening the end of the pipe in a generally 75 similar manner. The pipe may, if desired, of course, consist of a plurality of similar sections united in any suitable manner.

In Figs. 3 and 4 I have shown a somewhat 80 modified construction in which the constricted passages 3 are alternately disposed at right angles to each other in place of being formed in substantially the same plane as in Fig. 1. The inlet end of the muffler 85 may be provided with a collar 5 whereby it can be more readily connected to the main exhaust pipe of the engine.

The operation of the device is apparent. As the exhaust gas passes through the series 90 of substantially separated chambers, its explosive force is gradually broken up and the gas finally discharges noiselessly into the atmosphere in a relatively steady stream. By increasing the number of chambers an explosive force of any velocity can be so reduced as to be entirely obviated.

It is to be understood that the invention is not limited to the detail of construction shown except as set forth in the claims. 100

I claim as my invention:

1. In a muffler, the combination with a conduit provided with a plurality of elongated substantially closed chambers serially connected together by constricted passages 105 formed by flattening the sides of the conduit.

2. A muffler comprising a pipe having a plurality of elongated chambers serially communicating with each other through 110

constricted passages formed by flattening the sides of the pipe, said constricted passages being alternately disposed at right angles to each other.

5. 3. A muffler comprising a pipe having a plurality of elongated chambers serially communicating with each other through constricted passages formed by flattening

the sides of the pipe, a plurality of said passages being disposed at an angle to others of said passages.

WILLIE OWEN THOMAS.
